UNITED STATES PATENT OFFICE.

MILTON P. MILLER, OF DUBUQUE, IOWA, ASSIGNOR TO GEORGE D. WANNER, OF DAYTON, OHIO.

KITE.

Application filed February 11, 1927. Serial No. 167,385.

My invention has reference to kites, and has for its purpose to provide a novel toy of that kind which is convenient for use for commercial purposes. It is specially designed to be given away by mercantile establishments with a certain amount of goods purchased, and is provided with ample space to be employed for advertising purposes. With this use in view, it is so constructed that it can be transported and stored in a dismantled and compact condition, so as to occupy a minimum of space, and so that it can be readily assembled for use.

In the drawings:

Fig. 1 is a perspective view of the invention from above.

Fig. 2 is an end view thereof.

Fig. 3 is a detail of the plane formation.

Fig. 4 shows the device when rolled up into compact shape.

The invention consists of a body portion formed of parallel strips 1, provided at their ends with fabric 2 and 3, said strips being held in a triangular form by means of spreaders of a T formation, consisting of pieces 4 notched in their ends for engagement with the strips 1, and struts 5, notched in their ends for engagement with the other strips 1 and the spreaders 4. For this purpose the notches in the struts 5 are in planes at right angles with each other.

At one end of the body portion is a plane formed of a pair of strips 6 united near the ends thereof by struts 7, and provided with a sheet of fabric 8. The ends of the struts are notched for engagement with the strips 6, which are first turned inwardly as shown in Fig. 3 to form a hold for the strut. The plane is attached to body portion by means of cords 9, which are preferably of elastic, and which pass beneath two of the strips 1 in the central part thereof, and then round the projecting ends of the strips. The kite thus formed can be flown in the usual manner by means of a cord 10 attached to the kite at a point beneath the plane. No tail is required therefor.

A small propeller may be attached to the front edge of the plane, as shown at 11, if desired.

By slipping the ends of the cords 9 from the ends of the strips 1 the plane can be detached from the body portion, and by sliding one of the ends of the struts or spreaders 5 along the strip with which it is engaged it

can be readily released, permitting the body portion and plane to be collapsed. All of the parts, including the braces, can then be rolled into compact form, with the fabric of the plane serving as a casing therefor, as shown in Fig. 4. The parts can be as readily assembled again, when it is desired to use the kite.

The kite can be produced at a minimum of cost, and the various fabric portions thereof are available for the purpose of placing advertising material thereon. This is especially the case with the lower surface of the fabric 8, which is visible from the ground.

What I claim, and desire to secure by Letters Patent, is:

1. A kite comprising a plurality of body frame members extended parallel one with another in inverted triangular formation, a plurality of spreader frame members bifurcated at their ends and sustained frictionally transversely between the upper parallel members, a vertically extended strut bifurcated at its ends and sustained frictionally between each spreader member and the lower parallel member, and a plane structure supported upon the upper parallel members.

2. A kite comprising a plurality of body frame members extended parallel one with another in inverted triangular formation, a plurality of spreader frame members bifurcated at their opposite ends for interposing the spreaders detachably between the upper parallel members, a plurality of struts bifurcated at their opposite ends for interposing a strut detachably between each spreader and the lower parallel member, and a plane supported flexibly upon the upper parallel members.

3. A kite comprising a body portion including opposite parallel frame members disposed in a horizontal plane, and having forwardly extended ends, a plane supported on said members, and a band looped over said end of each member, extended over said plane and secured at the rear thereof to said member for supporting the plane yieldingly thereon.

4. A kite comprising a collapsible body structure and a collapsible plane structure, elastic elements supporting the plane on the body, said plane including parallel frame members spaced one from the other laterally and disposed at right angles to said body, and a plurality of bifurcated struts inter-

posed frictionally between the parallel members.

5. A kite comprising a collapsible body structure, a collapsible plane structure supported detachably on the body structure including parallel frame members spaced one from the other laterally and disposed at right angles to said body, a fabric cover over said

members with the opposite side edges thereof turned thereover, and a plurality of struts 10 interposed detachably between the parallel members with the ends of the struts pressed against said turned edges of the plane fabric.

In testimony whereof I affix my signature.

MILTON P. MILLER.
